ABSTRACT: The passages for the cooling device are of narrow dimensions so that the coolant passes through as a high speed film in order to avoid boiler scale and to increase the rate of cooling of the casting mold. The passages can extend across the mold or a number of parallel passageways can be distributed across the mold.

COOLING DEVICE FOR CONTINUOUS CASTING OF STRIP METAL

This invention relates to a cooling device for continuous casting of strip metal. More particularly, this invention relates to a cooling device disposed about a mold for continuously casting of strip metal.

Heretofore, molds have been operatively connected to furnaces containing molten metals or alloys for continuously casting the molten metal or alloy into strips. Generally, cooling devices of the water-cooled type have been disposed over the broad sides of these molds to cool the molds. However, these cooling devices have used relatively large chambers for the passage of the coolant water while the water has had a relatively low rate of speed in flowing through the chambers. This has led to the formation of boiler scale in the cooling devices and has thus caused accumulations of heat which can result in troubles in the continuous casting operation.

Accordingly, it is an object of the invention to substantially eliminate the formation of boiler scale in the cooling device of a continuous casting apparatus.

It is another object of the invention to increase the rate of flow of coolant through a cooling device of a continuous casting apparatus.

Briefly, the invention provides a cooling device for the mold of a continuous casting apparatus which cooperates with the mold to cool the mold by forming a narrow gap so that water flowing through the gap flows in a thin high speed film. The surfaces of the cooling device defining the gap extend substantially parallel to the plane of the strip being cast within the mold and across the width of the cooling device. The gap is of a thickness in the order of 0.5 to 1 mm. and the speed of the flow of water is from 2 to 20 meters per second.

Since the cooling water flows through the cooling device in the form of a thin film and at a high speed, the formation of boiler scale in the cooling device is eliminated. Thus, disturbances to the continuous casting operation are avoided in a simple and reliable manner. Further, as a result of the high speed of the cooling water, heat transfer is improved and the cooling effect is increased.

These and other objects and advantages of the invention will become more apparent from the following detailed description and appended claims taken in conjunction with the accompanying drawings in which:

FIG. 1 illustrates a longitudinal cross-sectional view of an apparatus of the invention; and

FIG. 2 illustrates a fragmentary transverse cross-sectional view of the apparatus of FIG. 1.

Referring to FIGS. 1 and 2, the mold 1 is constructed of two parts and is connected in a known manner at the left end as viewed in FIG. 1 to a furnace (not shown) containing molten metal or a molten metal alloy. The mold 1 is preferably made of graphite and is surrounded by a cooling device 2, 3 so that as molten metal flows into the mold 1 from the furnace the cooling device 2, 3 influences the metal to solidify into a strip 4. The strip 4 is moved out of the mold 1 either continuously or intermittently in the direction indicated by the arrow 5 by a suitable drawing device (not shown).

The parts of the cooling device 2, 3 extend above and below the broad sides of the strip 4 and abut against the mold 1 in heat transfer relation therewith. The parts 2, 3 are held together by suitable means, such as, screws, as indicated by the design lines 6 in FIG. 2 on opposite sides of the mold 1 in heat transfer relation therewith. Part 2 of the cooling device which is constructed in a similar manner to part 3 has a pair of recesses 7, the bottom surfaces 8 of which are substantially parallel to the plane in which the strip 4 moves. A cover 9 is disposed in each recess 7 with the underside 10 spaced from the surface 8 in parallel relation to form a narrow gap 13 of thickness of about 0.5 to 1.0 mm. and a length and width equal

to the underside extent of the cover 9. The surfaces 8, 10 defining the gap 13 constitute guiding surfaces for a stream of cooling water which enters from an inlet 11 in the cover 9 and exits from an outlet 12 in the opposite end of the cover 9. In flowing through the gap 13, the water forms a thin film and flows in a direction opposite to the movement of the strip 4 at a speed of from 2 to 20 meters per second.

The cover 9 is shaped to define a distribution chamber 14 with part 2 at the upstream end of the gap 13 and a collecting chamber 15 at the downstream end of the gap 13. The transition from the gap 13 to the collection chamber 15 is trumpet shaped in order to achieve a good cooling action as close as possible to the mold inlet.

The flow of water through the respective gaps 13 can be varied by varying the supply of water to the gaps so as to vary the cooling effect across the width of the strip 4. Also, in order to avoid blockage in the gaps 13, filtered water can be fed through the cooling device.

It is noted that while the cooling device is described as having several adjacent gaps transversely of the cooling device, each part of the device can also be constructed with only one gap extending substantially over the whole length of the cooling device.

It is also noted that packing seals of suitable construction can be inserted in a known manner between the edges of the covers 9 and adjacent surfaces of the cooling device parts 2, 3.

Further, instead of using a two part mold 1, a four part mold can be used in which each surface bounding the narrow side of the strip are formed by separate mold parts.

The invention thus provides a cooling device wherein a narrow gap is formed to conduct a thin film of coolant at relatively high speed. This substantially avoids the formation of boiler scale in the cooling device. Further, the invention allows an increase in the cooling effect by improving the heat extraction.

Having thus described the invention, it is not intended that it be so limited as changes may be readily made therein without departure from the scope of the invention. Accordingly, it is intended that the foregoing Abstract of the Disclosure and the subject matter described above and shown in the drawings be interpreted as illustrative and not in a limiting sense.

I claim:

1. A combination with a mold of porous material for horizontal continuous casting:

a cooling device comprising a pair of parts removably disposed on two opposite sides of said mold in abutment therewith, each said part having at least one narrow gap therein parallel to and spaced from said mold and means for directing the coolant through said gap, said gap being of a size to guide the flow of coolant within each part in a thin film at high speed; and means for holding said parts of said cooling device on opposite sides of said mold in heat transfer relation therewith.

2. The combination as set forth in claim 1 wherein said directing means includes a distribution chamber upstream of said gap and a collection chamber downstream of said gap.

3. The combination as set forth in claim 2 wherein said collection chamber has a trumpet shaped transition from said gap into said collection chamber.

4. The combination as set forth in claim 1 wherein said mold is made of graphite.

5. The combination as set forth in claim 1 wherein each part includes a recess therein having a bottom surface parallel to said mold, and a cover disposed in said recess having an underside spaced from said surface of said recess in parallel relation to define said gap.

6. The combination as set forth in claim 5 wherein said gap is of a thickness from 0.5 mm. to 1.0 mm.
